UNITED STATES PATENT OFFICE.

PAUL E. WIRT, OF BLOOMSBURG, PENNSYLVANIA.

SPRING ATTACHMENT FOR ARTICLES OF WEAR, &c.

SPECIFICATION forming part of Letters Patent No. 692,041, dated January 28, 1902.

Application filed August 29, 1901. Serial No. 73,665. (No model.)

To all whom it may concern:

Be it known that I, PAUL E. WIRT, a citizen of the United States, residing at Bloomsburg, in the county of Columbia and State of Pennsylvania, have invented certain new and useful Improvements in Spring Attachments for Articles of Wear, of which the following is a specification.

This invention relates to spring attachments for articles of wear and analogous uses, and more particularly has reference to that class of devices providing a spring or elastic action for articles of wear, such as suspenders and the like.

15 To this end the invention contemplates novel and practical forms of spring attachments primarily embodying the type of spring disclosed in my allowed application, Serial No. 59,453, filed May 9, 1901, and also presenting certain improved features contributing largely to the practicability and efficiency of the device for the purposes intended.

The present invention has in view the provision of such forms of spring attachment for 25 suspenders and the like which comprise means for giving such a free and lively spring action as to insure ease to the user of the article fitted with the invention while at the same time embodying a construction of spring and such 30 an arrangement of the attaching element or elements therewith as to provide for the greatest lengthening of the suspender or other article by the action of the spring within the most limited space and also with the least 35 possible friction upon the adjacent clothing.

In addition to the character of the spring and its general relation to the attaching element or elements, whereby the greatest possible efficiency is derived from the spring, the 40 present invention also contemplates novel and improved means for guiding the attaching element or elements and holding the same in proper relation to the spring-wire body of the attachment, whereby the friction incident to 45 the lengthening of the attaching element or elements under stress is reduced to a minimum.

Specifically speaking, the invention has in view the provision of antifriction-guides of a 50 pivotal or self-adjusting type and so mounted or arranged as to automatically or freely adjust themselves to the movement, plane, or

direction of the attaching element or elements, thus reducing friction and consequent wear upon the said attaching element or elements. In this connection it may be added that the self-adjusting guides afford full bearing-surfaces for the attaching element or elements to run over with the spring in any position, and consequently acute angles or turns 55 for the attaching element or cord are entirely obviated and liveliness is also materially added to the action of the spring itself.

With these and many other objects in view, which will readily appear as the nature of the 60 invention is better understood, the same consists in the novel construction, combination, and arrangement of parts hereinafter more fully described, illustrated, and claimed.

The fundamental features of the invention 65 are susceptible to embodiment in divers modifications without departing from the spirit or scope of the invention. However, for illustrative purposes the invention claimed is shown in a few of its preferred embodiments 70 in the drawings, in which—

Figure 1 is an elevation of one form of spring attachment shown applied to the front end of an inelastic suspender-strap, the view disclosing the combination of the self-adjusting guides with a single-coil type of spring-wire body. Fig. 2 is an elevation of the same form of attachment, showing the same under stress with the side arms of the spring-wire body drawn downward and close together, 75 thus providing for a considerable lengthening of the suspender, the view also indicating the manner in which the pivoted guides adjust themselves to the position of the attaching element or cord. Fig. 3 is a similar view of 80 the same formation of attachment shown under stress and at an angle, thus indicating the wide range of accommodation of the spring and its guides to stress exerted at different angles. Fig. 4 is a view similar to Fig. 85 1, illustrating a form exemplifying the novel combination of the wire body with a spring-coil, the terminal guides, and the arrangement of the attaching element or cord in a manner to exert a direct cross stress or pull upon the 90 terminals of the spring between the guides. Figs. 5 and 6 are views of the spring-wire body itself, showing a modification in the form of spring-coil, illustrating how the same 95

may be made of round or flattened wire to provide for less bulk in the spring should this be found necessary. Fig. 7 is a perspective view of another form of the invention, 5 showing how the self-adjusting guides may be associated with a cross-reeved arrangement of the attaching elements similar to the reeving disclosed in the allowed application aforesaid. Fig. 8 is a perspective view of the 10 form of spring attachment shown in Fig. 7, illustrating the several elements thereof disassociated to disclose one preferred means of pivotally connecting the self-adjusting guides with the terminals of the spring-wire body. 15 Figs. 9 and 10 are modifications of the invention, showing how the attaching elements in the cross-reeved arrangement may have a fixed connection with stress-points on the spring-arms instead of being connected directly with the self-adjusting guides. Fig. 20 11 is a perspective view of a modification, showing a novel manner of reeving separate attaching elements and associating the same with self-adjusting guides. Fig. 12 is a detail in perspective of one of the guides shown 25 in Fig. 11. Fig. 13 is an elevation of another form of parallel reeving, showing the attaching elements associated with pivoted guides. Fig. 14 is a detail in perspective of one of the 30 self-adjusting guides shown in Fig. 13.

Like numerals of reference designate corresponding parts in the several figures of the drawings.

It is of course understood that the invention 35 may be used in any practical or desired manner in connection with inelastic suspenders or like articles of wear where it is desired to secure a maximum resiliency and effective spring action, while at the same time providing for the greatest possible lengthening of the suspender or like article without losing or impairing the set of the spring. Hence in every embodiment of the invention it is of the greatest importance that the spring or the acting 45 spring portion, which is the coil or coils, be of such construction and arrangement as to be capable of withstanding great stress and wear without losing its set and at the same time being active or lively. These same characteristics 50 are necessary qualifications of the spring disclosed in my allowed application aforesaid, and the present invention has in view, as already stated, such embodiments of the spring attachment as accentuate the 55 improved and useful combination of the coiled spring body, the oppositely-extending side arms, the antifriction-guides, and the relation of the attaching element or elements thereto. All forms of the attachment embrace 60 this novel combination of elements, whereby a minimum of friction is insured for the movement of the attaching element or elements and at the same time the latter serve to exert a direct cross stress or pull 65 upon the terminals of the side arms between the guides carried thereby, whereby a maximum efficiency of spring action and a mini-

mum amount of friction are insured. As all forms of the attachment embody this combination, specific reference will first be made 70 to the simple forms best illustrating the same, said forms of the attachment being shown in Figs. 1 to 6, inclusive, of the drawings.

The numeral 1 designates the spring-wire body. This body is preferably formed of a 75 single length of spring-wire of any desired strength and weight, and the wire body formed of this length of wire is provided at a point between its ends with a plurality of convolutions forming a spring-coil 2, which 80 is offset laterally from the main length of wire and serves to greatly increase the resiliency of the body and also serves to cause the same to entirely resume its original set when completely relieved of stress or strain. As 85 far as the novel combination of elements above specified is concerned there may be one or a plurality of the spring-coils 2 between the ends of the spring-wire body; but inasmuch as the present application is for the 90 purposes of distinction and clearness restricted to the illustration of the single-coil forms of attachment only such forms will be specifically mentioned and shown. The spring-coil 2 may obviously be formed of any number of convolutions of spring-wire and also may be constructed of round or flattened wire, as indicated in Figs. 5 and 6, as may be found best adapted for a particular use; but irrespective of the specific formation of 95 the spring coil or coils the spring-wire body 1 is provided at opposite sides of the plane thereof with oppositely-extending yielding side arms 3. These oppositely-extending side arms 100 3 of the spring-wire body in their normal position preferably extend at approximately right angles to the offset spring-coil 2. In all forms of the invention these side arms are designed to carry at their terminals antifriction-guides 4 of some suitable form, which guides serve 105 to loosely and freely carry the flexible attaching element or elements 5, utilized to effect a connection between the spring-wire body and the pantaloons or other object to be yieldingly held or fastened through the 110 medium of the spring attachment.

In the forms of the invention shown in Figs. 1 to 4, inclusive, of the drawings the antifriction-guides 4 are shown as being pendent from the outer ends or terminals of the arms 3 of 115 the spring-wire body and are also illustrated as having associated therewith an attaching element or cord 5, consisting of a continuous single cord having a free play through both guides and provided at its terminals with the 120 usual tabs or loops 6 for connection with the buttons of a pair of trousers. With this combination of parts an efficient spring action and a maximum lengthening of the suspender are rendered possible. I am aware of the fact 125 that it is old in the art to associate guides with a spring-wire body having no coil and also to utilize therewith a continuous or single attaching element. This construction pro-

vides for an exceedingly poor spring action and renders it impossible to effect such a lengthening of the attaching element, as well as the maintenance of the original set of the 5 spring, as is provided for by the construction already described, in which there is associated with a spring-wire body having a spring coil or coils between its opposite arms guides at the terminals of said arms and an attaching 10 element having a loose running engagement through the guides and arranged to exert a direct cross stress or pull upon the terminals of the side arms between the guides and entirely within the plane intersecting both guides. 15 Every element of this construction and combination of parts contributes to producing the very efficient spring action and maximum lengthening of the suspender within a very limited space, as contemplated by the present 20 invention, and it should be further observed at this point that other factors of the invention which are of importance in securing the results described are, first, the normal disposition of the yielding side arms 3, in the preferred 25 construction these side arms in their normal positions projecting from opposite sides of the coil in substantially the same tangential plane and may therefore properly be said to normally lie substantially in alignment, and, second, in the portion of the attaching element between the guides being approximately coextensive in length with the combined lengths of the side arms, or, in other words, approximately coextensive in length 30 with the entire length of the body in its normal extended condition. All of these features co-operate together to produce a device providing for the maximum lengthening of the suspender within a restricted area, besides securing 35 a very lively and efficient spring action. This novel and efficient combination of elements in a spring attachment may be carried out with either fixed or self-adjusting antifriction-guides 4, and to emphasize this Fig. 4 of 40 the drawings is included in the illustration to show the terminals of the spring-arms 3 as being fitted with guides 4 of a fixed type. These guides are shown as essentially consisting of curved guiding-sleeves 7, having attaching- 45 50 elbows 8 fixedly fastened upon the ends of the spring-arms 3, although any other form of fixed guide may be embodied in the construction shown in Fig. 4. In addition to the combination described in connection with 55 the spring-wire body an important feature of the present invention resides in having the guides 4 of a self-adjusting or pivotal type. Broadly speaking, the self-adjusting guides 4 are pivoted upon axes disposed transversely 60 to the spring-arms carrying the same, whereby the guides turn or swing within the longitudinal plane of the spring-body toward and from each other in the direction of stress or pull. Consequently the said guides will 65 adjust themselves to the movement, plane, or direction of the attaching element or cord,

thus reducing friction and consequent wear upon the cord. Also, whatever position the spring may assume, the self-adjusting guides afford full bearing-surfaces for the attaching 70 elements to run over and entirely obviate acute angles or turns.

In the simple forms of the invention shown in Figs. 1 to 3 of the drawings the self-adjusting or pivotal guides 4 are shown as consisting of segmental or curved guiding-sleeves 9, having upstanding ears 10, pivotally connected with the terminals of the spring-arms 3 by means of the transverse pivot 11—that is, a pivot which is disposed transversely to the 80 longitudinal plane of the spring-arm carrying the same. This manner of pivotally hanging the self-adjusting guides from the ends of the spring-arms provides for said guides turning or swinging within the longitudinal 85 plane of the spring-wire body toward and from each other in the direction of stress or pull. Of course the self-adjusting guides may be constructed in any desired manner, and also may be pivotally mounted upon the ends 90 of the spring-arms in any manner, so long as they maintain the relation described to such arms; but a practical way of forming the self-adjusting guides is shown in detail in Fig. 8 of the drawings, in which the guide 4 95 is shown as consisting of a metal plate doubled upon itself and bent to form a segmental guiding-sleeve 9 and oppositely-arranged attaching-ears 10, which ears are perforated to receive the pivot or pivot-stud 11. In the 100 construction shown the pivot-stud 11 is fitted within an annularly-grooved pivot-washer 12, set within an eye 13, formed at the end of the spring-arm 3 by bending or looping the 105 spring-wire.

In the figure of the drawings just described a modified form of self-adjusting guide 4 is illustrated, adapted for a cross-reaved arrangement of the attaching elements, such as shown in my allowed application aforementioned. This modification simply consists in forming the metal body above the guiding-sleeve 9 with a socket portion 14, having at the sides thereof inwardly-bent prongs 15, designed to engage the ends of the crossing attaching elements or cords, thus providing holding members for the attaching elements contiguous to the guides which loosely receive the same. The construction described necessarily provides stress-points for the 110 crossing attaching elements contiguous to the guides, although in the arrangement shown in Figs. 7 and 8 of the present case the attaching elements are not connected directly to the yielding arms of the spring-wire body. 115 However, it is obvious that the self-adjusting or pivotal guides may be associated with crossing attaching elements, whose fixed ends are connected directly to the yielding arms of the spring-wire body by means of holding members, such modifications being shown in 120 Figs. 9 and 10 of the drawings, and the hold- 125 130

ing members on the spring-arms for the fixed ends of the elements being designated by the reference-number 16.

Figs. 7, 9, and 10 show the self-adjusting guides associated with a cross-reeved arrangement of the attaching elements similar to that disclosed in the allowed application; but in the modification shown in Figs. 11 and 12 of the drawings there is illustrated a form of self-adjusting guide 4 having the guiding-sleeve 9^a and the holding member or socket 14^a arranged side by side in the same transverse plane, thus making it possible for the oppositely-arranged attaching elements 5 to be reeved in opposite directions, but in parallel relation side by side, whereby crossing of the attaching elements or cords is entirely obviated. Likewise in the modification shown in Figs. 13 and 14 of the drawings another form of self-adjusting or pivotal guides is illustrated in which the guiding-sleeve 9^b and the holding member or socket 14^b are arranged in substantially the same relation as shown in Fig. 7, but the separate attaching elements or cords are disposed in parallel relation one above the other to obviate the direct crossing of the elements or cords. These additional modifications show the possibilities of use of single and a plurality of attaching elements with self-adjusting antifriction-guides; but as the specific reeving of attaching elements shown in Figs. 11 to 14 of the drawings can obviously be employed with fixed or pivotal guides this manner of reeving is not specifically claimed in the present application.

Various other modifications of the invention may be resorted to without departing from the spirit or scope thereof, and it will be understood, therefore, that changes in the form, proportion, and minor details of construction may be made without departing from the principle or sacrificing any of the advantages of the invention.

Having thus described my invention, what I claim as new, and desire to secure by Letters Patent, is—

1. A spring attachment of the class described, comprising a spring-wire body having a spring-coil and oppositely-projecting yielding side arms extended from the terminals of the coil, at opposite sides thereof, and normally lying substantially in alignment, antifriction-guides located at the outer terminals of the side arms, and an attaching element arranged to exert a direct cross stress or pull between the guides upon the terminals of the side arms, the portion of said element between the guides being approximately coextensive in length with the body in its normal extended condition.

55

2. A spring attachment of the class described, comprising a spring-wire body having oppositely-extending yielding side arms, self-adjusting antifriction-guides carried by said arms and having an independent movement within the plane of the body in a direction toward and from each other, and a flexible attaching element.

60

3. A spring attachment of the class described comprising a spring-wire body having oppositely-extending yielding side arms, self-adjusting guides pivotally carried by the terminals of said arms and having axes disposed transversely thereto, and a flexible attaching element.

70

4. A spring attachment of the class described comprising a spring-wire body having oppositely-extending yielding side arms, self-adjusting pendent guides pivotally suspended from the terminals of said arms and having their axes disposed transversely of the latter whereby the guides will turn or swing within the longitudinal plane of the body in the direction of stress or pull, and the attaching element.

75

5. A spring attachment of the class described, comprising a spring-wire body having oppositely-extending side arms, pivot-washers fitted to the terminals of the side arms, pendent self-adjusting guides consisting of metallic blanks bent to provide guiding-sleeves and oppositely-arranged attaching-ears, pivots connecting said attaching-ears, with the pivot-washers, and the attaching element.
